UNITED STATES PATENT OFFICE.

CHARLES JAMES BRODIE, OF WAVERLY, IOWA.

SNOW-SCRAPER.

1,114,442.

Specification of Letters Patent.

Patented Oct. 20, 1914.

Application filed February 28, 1914. Serial No. 821,800.

To all whom it may concern:

Be it known that I, CHARLES JAMES BRODIE, citizen of the United States, residing at Waverly, in the county of Bremer and State 5 of Iowa, have invented certain new and useful Improvements in Snow-Scrapers; and I do hereby declare the following to be a full, clear, and exact description of the invention, such as will enable others skilled in the art 10 to which it appertains to make and use the same.

This invention relates to scrapers, and while especially adapted and intended for scrapers to be employed for removing snow 15 from ice for harvesting, it is not limited to such use or such purpose and is applicable to any form of scraper where it is desired to scrape and remove material from a given surface.

20 An object of the present invention is to provide a frame to which draft may be applied with wings pivoted thereto meeting at the rear in a V and with means for releasing the wings to permit them to assume 25 substantially parallel positions to discharge the load and also to serve as runners for transportation of the scraper.

With these and other objects in view the 30 invention comprises certain novel constructions, combinations and arrangement of parts as will be hereinafter more fully described and claimed.

In the drawings: Figure 1 is a top plan view of the improved scraper with the wings 35 closed. Fig. 2 is a view of the scraper in end elevation as indicated by arrow 2 at Fig. 1. Fig. 3 is a top plan view of the scraper showing the wings open in parallel position for discharging the load and transportation. Fig. 4 is a sectional view taken 40 longitudinally centrally through the device as indicated by line 4-4 of Fig. 3.

Like characters of reference designate corresponding parts throughout the several 45 views.

The improved scraper which forms the subject matter of this application comprises a frame which may be of any approved or desired form or construction, here shown 50 as comprising a cross beam 10 substantially straight, and a curved beam 11 connected with the beam 10 at its opposite ends and spaced centrally therefrom by parallel-bars 12. These beams are preferably of angle 55 iron as shown, and their lower edges stand in a single horizontal plane.

A pole 13, or any approved form of attaching draft to the frame is provided so that the frame may be moved over the surface which it is desired to clean. 60

At its opposite ends the frame composed of the members 10 and 11 is provided with downwardly extending pintles 14 upon which the front ends of wings 15 are pivoted in any approved manner as by employing a bracket 16 secured to the exterior of each of said wings and having eyes through which the pintles 14 extend. Each wing stands upright beneath the framework and is firmly supported on the pivot at its front 70 end, its upper edge passing under and in contact with the beams 10 and 11 above, whatever the position of the wing, and by this means the framework is supported on the wings. It will be noted that the wings 75 15 are so proportioned that when they are brought together with their rear ends contacting as shown at Figs. 1 and 2 they form a V-shaped body under the frame. To maintain the wings in such relation flexible members as the chains 17 are employed secured to the wings in any approved manner as by employing a strengthening rib 18 and eye-bolts 19 with the chains passing over a roller 20 at the front of the frame and rearwardly 80 to a winding drum 21 mounted on the rear of the frame. The winding drum is provided at one end with a ratchet 22 as shown particularly at Fig. 3 with a detent 23 which is carried by a lever 24 standing adjacent a 85 seat 25 upon which the driver is supposed to ride.

With the device assembled as shown at 90 Figs. 1 and 2 it is driven across the ice or other surface to be cleaned until the wings 95 15 are loaded with snow or other material and is then driven off to some location where the load may be dumped without detriment. Arrived at such location the lever 24 is lifted which releases the winding drum 21 100 and permits the wings 15 to swing outwardly to parallel position as shown at Fig. 3, such swinging being facilitated by the load and the position is such that the wings are then moved with the frame leaving the 105 load where it is dumped and also serving as runners for the device while being returned to position for another load. When arrived at the position where the cleaning is to be continued the wings are returned 110 to the position shown at Fig. 1, the chain wound about the winding drum and re-

tained by the detent 23 when the device is again ready to perform its operation as above described.

I claim:

- 5 In a scraper, the combination with a framework comprising a straight cross beam and a curved beam in rear of and connected at its ends with said straight beam, the lower edges of the beams standing in a single horizontal plane, means for applying draft to said framework, and a roller and winding drum mounted on such framework; of pintles depending rigidly from opposite ends of the framework, two wings standing on edge beneath the framework, a
- 10
- 15

bracket secured to the exterior of each wing at its front end and having eyes journaled on one of said pintles, the upper edge of the wing sliding beneath said beams, and a chain connected with the rear end of the 20 wing and passing over said roller to the winding drum.

In testimony whereof I affix my signature in presence of witnesses.

CHARLES JAMES BRODIE.
